UNITED STATES PATENT OFFICE.

WILLIAM L. McGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed March 1, 1919. Serial No. 279,982.

To all whom it may concern:

Be it known that I, WILLIAM L. McGRATH, a citizen of the United States, residing at Elmira, in the county of Chemung 5 and State of New York, have invented certain new and useful Improvements in Engine Starters, of which the following is a specification.

My invention relates to starters for internal combustion engines or the like, and the particular object thereof is to improve the drive or transmission thereof. The drive with which my invention is concerned is of the automatic screw shaft type characterized by a rotatable screw shaft driven by a starting motor and having screw-threaded thereon a pinion adapted to be automatically advanced into mesh with an engine driven member such as the fly wheel, by the rotation 15 of such screw shaft. This pinion is loosely threaded upon the screw shaft so that it will not be inclined to bind thereon at the time when the pinion is to be rotarily idle and to be advanced longitudinally as above 20 stated. When the pinion is in full mesh with the fly wheel it is desirable that such pinion shall be accurately centered on the shaft and shall be firmly supported thereby, in order to properly mesh with the fly wheel and 25 also to avoid noise during their rotary movement as well as to prevent wear between the pinion and the screw shaft. According to 30 my present invention I attain this object by providing at one end of the screw shaft 35 a part (integral or separate from the shaft) which accurately fits a plain counterbored portion of the central bore of the pinion. The invention may be embodied in different forms of constructions, several of which are 40 herein shown and described.

In the drawing Fig. 1 is a sectional plan of a starter including a drive embodying my invention; Figs. 2 and 3 sections on the line 2—2, 3—3 of Fig. 1; Fig. 4 a detail 45 view in elevation of the stop nut and sleeve and a portion of the screw shaft; Figs. 5, 6 and 7 detail sections of modifications of the same general type; Fig. 8 a sectional elevation of a modification of another type, 50 and Fig. 9 a section on the line 9—9 of Fig. 8.

Referring to the embodiment of my invention as shown in Figs. 1 to 4, the drive illustrated comprises a driving shaft 1 which 55 may be the extended armature shaft of a

starting motor A, a driving head 2 secured to the outer end of the driving shaft, a coiled driving spring 3 secured to a screw shaft 4 which is in the form of a hollow sleeve mounted on the driving shaft, a pinion 5 screw-threaded upon the screw threads 4^a of such shaft and adapted to mesh with the teeth 6^a of the fly wheel 6 or other engine driven member.

The stop nut 7 instead of being an ordinary collar secured to one end of a screw shaft to form an abutment or stop for the pinion is provided with a cylindrical extension 7^a projecting towards the pinion. This stop nut is secured to the screw shaft 70 in any suitable manner as by means of threading. The pinion is provided with a central bore which is screw-threaded for a portion of its length to loosely fit the screw threads on the shaft, and is counterbored at 5^a for a portion of its length, which counterbore is of a diameter to rather accurately fit the cylindrical extension for the purpose of centering the pinion at the end of its longitudinal movement for meshing, and also of forming a solid and continuous support for such pinion during its rotation when driving the fly wheel. By preference the outer corner of the cylindrical extension is inclined or beveled at 7^b 85 to assist the pinion in the centering operation. The relative length of this extension and counterbore are such that at the end of its longitudinal movement to the left the end of the pinion will abut against the annular shoulder 7^c of the stop nut which thus receives all of the stopping contact and pressure of the pinion.

According to the modification shown in Fig. 5, the centering means is an integral 95 part of the screw shaft itself, comprising plain portion 4^b of suitable diameter which means the same or larger diameter than the outside diameter of the screw threads 4^a, but, in the present instance, of slightly 100 larger diameter. The counterbore 5^a of the pinion fits over this portion 4^b in the same way and with the same results as in the case of the other form of construction. In this construction, the stop shoulder 4^c is integral 105 with the shaft but obviously may be formed by a separate nut, like nut 7^d as shown in Fig. 6. In Fig. 7 I have shown another modification of the same general type as above described but differing from that of 110

Fig. 1 in that the stop nut 8 is of plain form. The centering and supporting means is a plain ring 9 interposed between said nut and the end of the screw threads 4^a. This particular construction has the advantage of economy and facility in manufacture inasmuch as the ring, being separate, can be separately machined or ground and treated.

By means of my invention I am enabled to obtain the advantage of a loose fit between the threads of the screw shaft and the pinion and to provide for the proper positioning and support of such pinion during the time when it is in driving operation.

In Figs. 8 and 9 I have shown a modified construction of a somewhat different type of drive according to which the pinion is not screw-threaded on a shaft but is controlled in its operation by a nut or control member which is screw-threaded onto such shaft. Referring to Fig. 8, the motor has an extended armature shaft which consists of a plain portion 10 and a screw-threaded portion 11. The pinion 12 slides on said plain portion and is controlled by the nut 13 which is screw-threaded on said screw shaft and is connected to the pinion by the driving spring 14.

As shown the pinion does not fit the outer end of the plain portion of the shaft with any accuracy or closeness but has a loose fit therewith when in its normal or home position thereby leaving an annular space 15 between the pinion and the shaft 10, as illustrated. However, the inner portion of this shaft is slightly enlarged in diameter and carefully machined so that the pinion bore will fit accurately thereon when it is in mesh with the fly wheel. This enlarged portion is indicated at 10^a and the result thereof is substantially the same with respect to the action of this pinion as in respect to the pinions of the previously described constructions.

I claim:

1. In an engine starter, a drive or transmission including a screw shaft, a driving member screw-threaded thereon for longitudinal movement along the shaft to engage a member of the engine to be started, and a stop nut secured to the screw shaft and having an extension projecting towards the driving member, which latter has a counterbore adapted to fit upon such extension.

2. In an engine starter, a drive or transmission including a screw shaft, a driving member screw-threaded thereon for longitudinal movement along the shaft to engage a member of the engine to be started, and a stop nut secured to the screw shaft and having a cylindrical extension of less diameter than the nut, such driving member having a counterbore adapted to fit upon the sleeve.

3. In an engine starter, a drive or transmission including a screw shaft, a driving member screw-threaded thereon for longitudinal movement along the shaft to engage a member of the engine to be started, and a stop nut secured to the screw shaft and having an extension projecting towards the driving member, which has a counterbore adapted to fit upon such extension, the outer corner of said extension being shaped to insure centering of the driving member.

4. In an engine starter, a drive or transmission including a screw shaft, a driving member screw-threaded thereon for longitudinal movement along the shaft to engage a member of the engine to be started, and a stop nut secured to the screw shaft and having an extension projecting towards the driving member, which has a counterbore adapted to fit such extension, said counterbore being longer than the extension to permit the driving member to abut the stop nut itself.

WILLIAM L. MCGRATH.
